UNITED STATES PATENT OFFICE.

ROBERT M. CRAIG, OF PATERSON, NEW JERSEY.

CONCRETE-MIXING MACHINE.

1,321,890.

Specification of Letters Patent. Patented Nov. 18, 1919.

Application filed November 18, 1918. Serial No. 262,404.

To all whom it may concern:

Be it known that I, ROBERT M. CRAIG, a citizen of the United States, residing at Paterson, in the county of Passaic and State of New Jersey, have invented certain new and useful Improvements in Concrete-Mixing Machines, of which the following is a specification.

This invention consists in a novel combination of elements, including a rotary part 10 rotating on a horizontal axis (as the drum of a concrete mixing machine) and a part to be actuated (as closure means for the outlet of such drum, or a signal device for a concrete mixing machine), whereby actuation 15 will be transmitted automatically from said rotary part to the part to be actuated, the object being to effect the desired actuation when the rotary part has performed a predetermined number of revolutions.

In the accompanying drawings,

Figure 1 is a side elevation of the machine;

Figs. 2 and 3 end views thereof, the delivery spout being omitted and the superstructure broken away in Fig. 3;

Figs. 4, 5 and 6 illustrate details of a certain power transmitting means; and

Fig. 7 is a detail of the means for controlling the water supply.

On rotary supports *a* journaled in a suitable frame *b* rest the circular treads *c* of a mixing chamber *d* in the form of a spheroidal drum open at both ends; one or more of the supports *a* may have teeth to mesh with teeth on the corresponding tread *c* and afford the means whereby to drive the drum from any suitable source, as a small engine (not shown). There is a delivery spout *f* below the opening in a valve-frame *g* fixed to frame *b* opposite the (delivery) opening in one end of the drum, and this valve-frame has mounted therein any suitable gate or valve, that shown consisting of a pair of wings *h* *h'* geared together, as at *i*, the former having a weighted handle *j* and a lever *k* projecting in different directions; gravity holds the wings in the closed position, but a slight displacement of the wings toward the open position, as by movement of lever *k* to the right in Fig. 3, will shift element *h*—*j*—*k* past a perpendicular through its center of gravity so that said element will swing over and move wing *h'* with it, to open position. *l* is a chute or movable hopper pivoted at *m* in frame *b*, being provided with an open-

ing *m'* into which the solids to be mixed are shoveled and being adapted when uplifted to chute its contents into the (receiving) opening at the left end of the drum in Fig. 1. It 60 may be raised and lowered by any suitable means, *n* being a cable forming part of such means and extending over the sheaves *o*. It is equipped with a transverse fixed bar *p* having cam-block *q* with an inclined face. 65

At the delivery end of the machine there is attached to the frame a gong *r* having a hammer *s* in the form of a lever against one arm of which bears a spring *s'* normally pressing the other arm toward the gong. 70

The rotary structure which comprises drum *d* and its treads also includes a clip *t* secured to a central rib *u* which extends entirely around the drum, there being arranged in the clip a tappet bar *v* which is parallel 75 with the axis of the drum and may be adjusted longitudinally in the clip by manipulating a set-screw *w* (Fig. 4).

Between the said rotary structure on the one hand and the gate (specifically, lever *k*) 80 and hammer *s* on the other there is a power transmitting connection constituted as now to be described:

x is a rotary shaft having fixed thereon a star-wheel *y*. Its left hand end portion is 85 threaded, at *z* (Fig. 5) and is supported by beveled blade or knife *z'* attached to the frame *b*; its right hand end portion is journaled in a bearing *z*² preferably pivoted in a bracket *c*³ on a horizontal axis transverse to the shaft. This shaft may be shifted to the right until the star-wheel will be engaged on each revolution of the drum by the tappet bar *v*, with the obvious result that the shaft will be fed by the engagement of knife 90 *z'* with its threading to the left until the star-wheel clears the tappet bar and so will no longer be rotated. On the right hand end of the shaft is adjustably secured a dial 2 carrying a tappet 2'. The free end of the 95 hammer *s* lies in the circular path of movement of this tappet, also in the circular path of the tappet is the free arm of a lever 3 pivoted to the frame and having its other arm underlying a projection *k'* on the free 100 end of the lever *k*, undue movement of lever 3 being prevented by a spring 4 and a stop 5 (Fig. 3). There is an elongated ratchet 6 secured on the shaft with which a pawl 7 pivoted to a portion of the frame is engaged 105 to prevent backward rotation thereof.

It should be remarked that the drum is

internally provided with some well-known means, as spiral blades, for urging the batch toward the delivery outlet thereof.

Following the delivery of each batch the 5 shaft x stands in the position shown in Fig. 1 with the star-wheel y clear of the tappet bar v . When the solids have been shoveled into the chute l , which is then depressed, it is elevated by means of its cable and the inclined face of cam-block q wiping against the end of the shaft x raises it clear of the knife, whereupon the bar p pushes the shaft to the right to bring the star-wheel in the path of movement of the tappet bar on the 10 drum which is being constantly rotated; meanwhile the chute is delivering its contents into the drum and when this is accomplished it is returned to its depressed position, so that the knife or blade z again 15 engages the threads of the shaft. The shaft x , by the engagement of the tappet bar v with the star-wheel, now rotates step by step, to wit until by the engagement of the threads z with the knife the star-wheel 20 has progressed far enough to the left to clear the tappet bar; but just before this occurs the tappet $2'$ first wipes over the free arm of the hammer s , which strikes the gong r as soon as the tappet clears it, and then over 25 the free end of lever 3 , which thereby imparts a sufficient impulse to lever k to effect opening of the gate wings h h' in a manner sufficiently explained before. The signal having been given and the batch being 30 now delivered, the operator closes the gate by means of the handle j preparatory to recharging the drum by again elevating the chute, into which it will be understood a fresh charge of solid materials has been 35 placed. It will be apparent that the time required for mixing may be varied by adjusting the dial and star-wheel longitudinally of the shaft, so that the opening of the gate and sounding of the alarm and the ensuing stopping of the shaft x may occur 40 on the lapse of any desired period of time after the shaft begins to be rotated step by step by the drum. The purpose of having the star-wheel clear the tappet bar v when 45 the gong has been sounded and the gate opened is to insure the tappet $2'$ stopping always at substantially the same point in its cycle, thereby to insure the mixing periods being all of the same length for a given 50 quantity of materials to be mixed.

A water tank 9 is arranged on the frame b above the drum and has an outlet 10 leading into the intake end of the drum. This outlet has a valve 11 which is suitably con-

nected to a lever 12 in turn suitably connected to the crank 13 on one end of a shaft 14 journaled in the frame and having at its other end a crank 15 which is connected with one arm of a bell-crank lever 16 by a pitman 17 , the other arm of said lever 15 being opposed by the end of a bar 18 which is guided in the frame and normally pressed toward the chute end of the machine by a spring 19 . When the chute rises it pushes the bar 18 endwise and so opens the valve. According 60 as it takes more or less time to deliver the solid contents of the chute, depending on the quantity thereof, so more or less water will be delivered into the drum with the contents of the chute. 65

Having thus fully described my invention, what I claim as new and desire to secure by Letters Patent is:—

1. In combination, a fixed structure, actuating means arranged therein and including a part rotating on a horizontal axis and having a tappet bar v arranged eccentrically of and parallel with said axis, a part to be actuated, and means to transmit actuation from the tappet bar to the part to be 80 actuated consisting of a screw device journaled parallel with said axis in, and having its threads engaged by a part of, said structure and on being rotated being thereby advanceable longitudinally of its 85 axis of rotation, said screw device being engageable and thereby adapted to be rotated by said tappet bar and also adapted during its longitudinal movement to engage and thereby actuate the part to be actuated. 90

2. In combination, a fixed structure, actuating means arranged therein and including a part rotating on a horizontal axis and having a tappet bar v arranged eccentrically of and parallel with said axis, a part to be 100 actuated, means to transmit actuation from the tappet bar to the part to be actuated consisting of a screw device journaled parallel with said axis in, and having its threads engaged by a part of, said structure 105 and on being rotated being thereby advanceable longitudinally of its axis of rotation, said screw device being engageable and thereby adapted to be rotated by said tappet bar and also adapted during its longitudinal movement to engage and thereby 110 actuate the part to be actuated, and means to engage and reset the screw-device longitudinally of its axis and contrary to its advancement. 115

In testimony whereof I affix my signature.

ROBERT M. CRAIG.
